UNITED STATES PATENT OFFICE.

WILLIAM M. BURKLE AND WILLIAM C. YEAGER, OF NEW HAVEN, CONNECTICUT.

POWDER-DIVIDER.

993,436.

Specification of Letters Patent. Patented May 30, 1911.

Application filed May 26, 1910. Serial No. 563,513.

To all whom it may concern:

Be it known that we, WILLIAM M. BURKLE and WILLIAM C. YEAGER, citizens of the United States, and residing, respectively, at 5 706 Dixwell avenue, in the city of New Haven, county of New Haven, and State of Connecticut, and No. 527 Congress avenue, in the city of New Haven, county of New Haven, and State of Connecticut, have 10 invented certain new and useful Improvements in Powder-Dividers, of which the following is a specification.

Our invention relates to improvements in powder dividers and the object of our invention is to divide and measure any desired quantity of powder with greater accuracy and rapidity than has heretofore been obtained, and to divide and measure the said desired quantity any desired number 20 of times without any difference in weight or in the number of grains measured between each or any of the measurements made, and to obviate the necessity of having several sized dividers, and to obviate the 25 necessity of a re-adjustment of the parts from time to time, as is necessary in the cases of former inventions.

The details and advantages of this invention will be pointed out in the following 30 specification, reference being had to the accompanying drawings in which—

Figure 1 is an elevation of our invention with the ejector pressed down: Fig. 2 is an elevation of our invention with the ejector held in place for the purpose of dividing the powder: Fig. 3 is a section upon the line X—X of Fig. 1 but with the parts in the positions occupied by them in Fig. 2: Fig. 4 is an enlarged plan of adjuster c: 40 and Fig. 5 is a sectional view of Fig. 4 on the line y—y.

The body a, is equipped with the slots g, in which slots g, are inserted the extensions i, and j, of the adjuster c. The adjuster c, is equipped with the binder screw d, and the threaded interior h, and the extensions i and j, is held in place against the closed head of body a, by the spiral spring e. The spiral spring e, is supported by the bar l, which is inserted into and extends through the body a.

The ejector b, is equipped at the upper part with a screw thread and at the bottom with the disk f, which disk (f) fits snugly 55 in the chamber m, the said ejector screws

into the adjuster c, at the threaded interior h, and passes through the bar l, and when properly adjusted as may be desired, is held in place and bound by the binder screw d. The binder screw d, is operated by 60 screwing it into the adjuster c, and against the ejector b, holding the said ejector b, in place.

The extensions i and j, of the adjuster c, fit snugly in the slots g, of the body a, the 65 slots g, acting as guides for the operative raising and lowering of the adjuster c. The stop o, on the ejector b, is provided for the purpose of preventing the possibility of the disk f's protrusion beyond the mouth of the 70 body a, and for the additional purpose of preventing the disk f from catching on the under side of said mouth.

The divider is used by adopting the following indicated method of operation. Having 75 filled the chamber m, from the mouth of the body a, to the bottom of the disk f, the powder is ejected by placing the open end or mouth of the body a, into the receptacle; and by applying pressure of the 80 thumb on the top of the ejector b, and holding the divider by the bar l, the ejector is forced downward until the lower surface of the disk f, by reason of the stop o, on the 85 ejector b, is a small fraction of an inch below and beyond the extremity of the chamber m, at the mouth of the body a, carrying the powder before it and depositing the powder in the receptacle. The spiral spring e, then raises the ejector b, to its original 90 position. If a change in the quantity of powder is desired the binder screw d, may be loosened, and the ejector b, may be rotated in either direction, according to whether a smaller or greater quantity of 95 powder is desired, thus increasing or decreasing the size of the space in the chamber m, between the lower surface of the disk f, and the mouth of the body a; this is accomplished by reason of the screw thread 100 on the upper end of the ejector b, which screw thread fits and rotates within the adjuster c, at the threaded interior h. When the desired dividing capacity of the chamber m, between the lower surface of the disk f, and the mouth of the body a, is obtained, the ejector is held in place by screwing the binder screw d, into the adjuster c and against the ejector b, until the ejector b, 105 is held rigidly.

Having thus described our invention, what we claim is,—

1. A powder dividing instrument consisting of a body *a*, slots *g*, a powder chamber *m*, a handle bar *l*, extending through said body *a*, an ejector *b*, operating within said chamber *m*, whereby the powder is ejected from said chamber *m*, substantially as described.
2. A powder dividing instrument consisting of a body *a*, slots *g*, a powder chamber *m*, a handle bar *l*, extending through said body *a*, an ejector *b*, whereby the powder is ejected from said chamber *m*, said ejector *b* having a piston *f* at one extremity and a stop *o* at the other extremity, and a screw shank between said piston *f* and stop *o*, substantially as described.
3. A powder dividing instrument consisting of a body *a*, slots *g*, a powder chamber *m*, a handle bar *l*, extending through said body *a*, an ejector *b*, whereby the powder is ejected from said chamber *m*, said ejector *b* having a piston *f* at one extremity and a stop *o* at the other extremity, and a screw shank between said piston *f* and said stop *o*, said body *a* having an adjuster *c*, said adjuster *c* consisting of the extensions *i* and *j*, a screwed interior *h* and a binder screw *d*, substantially as described.
4. A powder dividing instrument consisting of a body *a*, slots *g*, a powder chamber *m*, a handle bar *l*, extending through said body *a*, an ejector *b*, whereby the powder is ejected from said chamber *m*, said ejector *b* having a piston *f* at one extremity and a stop *o* at the other extremity, and a screw

shank between said piston *f* and said stop *o*, said body *a* having an adjuster *c*, said adjuster *c* consisting of the extensions *i* and *j*, a screwed interior *h* and a binder screw *d*, 40 said adjuster *c* engaging the screwed shank of the ejector *b* at any desired point on said screwed shank and held at the said desired point by the binder screw *d*, said extensions working perpendicularly within said slots *g*, 45 substantially as described.

5. A powder dividing instrument consisting of a body *a*, slots *g*, a powder chamber *m*, a handle bar *l*, extending through said body *a*, an ejector *b*, whereby the powder is ejected 50 from said chamber *m*, said ejector *b* having a piston *f* at one extremity and a stop *o* at the other extremity, and a screw shank between said piston *f* and said stop *o*, said body *a* having an adjuster *c*, said adjuster *c* consisting of the extensions *i* and *j*, a screwed interior *h* and a binder screw *d*, 55 said adjuster *c* engaging the screwed shank of the ejector *b* at any desired point on said screwed shank and held at the said desired point by the binder screw *d*, said extensions working perpendicularly within said slots *g*, said body *a* having a spring *e*, said spring *e* being confined within said body *a* and resting on the handle bar *l* and extending up to 60 and coming in contact with said adjuster *c*, substantially as described.
